UNITED STATES PATENT OFFICE

JAMES NICOLSON BAILEY, OF CHORLTON-CUM-HARDY, ENGLAND, ASSIGNOR TO METROPOLITAN-VICKERS ELECTRICAL COMPANY LIMITED, A COMPANY OF GREAT BRITAIN

APPARATUS FOR THE HEAT TREATMENT OF PULVERULENT MATERIALS

Application filed March 28, 1928, Serial No. 265,256, and in Great Britain March 29, 1927.

The invention relates to the heat treatment of pulverulent materials, and has for an object the provision of improved means for use for example in the carbonization of pulverized fuel.

5 A further object of the invention is the provision of an improved retort of more simple and compact form than those hitherto employed for this kind of heat treatment, whereby intimate contact between the solid 10 particles and gaseous media is assured in a uniform manner, if desired with the aid of an improved feeding and distributing device for the material to be treated.

15 Further objects of the invention include the provision of means for effecting separation of the solid and volatile constituents of the contents of the retort at appropriate stages of the treatment, and an improved retort for fractional distillation processes.

20 Various proposals have been made for the low temperature carbonization or distillation of coal, which entail bringing the coal in finely divided state into contact with a current of hot gases, the object being eventually 25 to obtain powdered coke suitable for use in boiler furnaces and the like, and advantageously also various by-products, including gas for use in the carbonization of further coal by the same treatment. In one proposed apparatus the pulverized coal falls into a stream of hot gas by which it is carbonized while being carried along in suspension through pipes terminating in an upwardly 30 expanding chamber where carbonization is completed, the powdered coke being finally extracted from the gaseous products by means of a cyclone separator. The expansion chamber enables the heavier particles of coke to 35 remain longer in contact with the hot gases and also effects relative movement between the particles and the gaseous stream constituting the fluid vehicle. In other apparatus the powdered coal is delivered into the upper 40 end of vertical retorts in which it is carbonized while falling through rising currents of hot gas.

45 According to the present invention the heating of the pulverulent material is effected 50 in a retort comprising a vortex chamber in

which the hot gases and the pulverized material are subjected to a violent whirling action whereby they are brought into intimate contact before being passed into a settling chamber, cyclone or other form of separating device to separate the treated pulverulent material from the fluid vehicle. Alternatively separation may be wholly or partly effected by one or more stages in the retort itself, which affords particular advantages where the fractional distillation of pulverized fuel is concerned.

55 The invention also provides a retort and a device for feeding the pulverulent material into the retort, comprising a nozzle device through which said material is ejected in the desired direction by gas under pressure. A valve may be provided for controlling the 60 supply of said material.

65 Thus the pulverulent material is thoroughly 70 mixed with the hot gases and remains in contact therewith a sufficient time to effect the desired coking and separation of the volatile materials, the retort being, however, of relatively small dimensions and of simple and inexpensive manufacture.

75 These and further features of the invention will be apparent from the following description with reference to the accompanying drawings, wherein Fig. 1 shows in vertical section a simple form of retort chamber and feeding device according to the invention, Fig. 2 shows also in vertical section a multi-chamber retort particularly suited for treatment involving frictional distillation, 80 Fig. 3 is a similar view showing a further modified form of retort according to the invention and Fig. 4 is a horizontal section on the line IV—IV of Fig. 1.

85 Referring to Fig. 1, the vortex chamber 1 is formed of inverted pear-shape and has a number of gas inlet ports 2 arranged more or less tangentially as shown in Fig. 4 in the walls at the part of greatest diameter, the gas being supplied through an annulus 3 which embraces the chamber 1 externally. 90 With this arrangement the axis of the vortex produced is vertical. Alternatively or in addition to the use of tangentially directed gas inlets for producing the vortex, vanes 95 100

or deflectors may be arranged in any desired manner in the retort for directing the incoming gas, as will be apparent. The powdered material to be treated is fed through a hopper 4 at the top of the retort chamber 1, and after treatment leaves together with the gases by way of an outlet at the bottom of the chamber.

The temperature of the hot gases entering the vortex chamber through the ports 2 is dependent upon the character of material to be treated and the results desired. For example, in the distillation of powdered coal, the temperature may be approximately 1300° F. It is to be understood however that this figure is not to be considered as limiting the invention.

For the purpose of controlling the supply of powdered material to the retort and to ensure its desired distribution therein a distributing device is employed comprising an ejector operated by compressed gas. The distributing device is mounted upon the end of a conduit 5 leading from the hopper 4 to a point at or near the centre of the retort 1 and comprises a cup-shaped casing 6 into the centre of which projects a compressed gas inlet tube 7 arranged concentrically within the conduit 5 for the powdered material. Nozzle-like outlets 8 through which said material is ejected by the gas are formed between the upper portions of the cup 6 and the lower end of the conduit 5, and in the construction shown are provided with guide vanes 9 curved to direct the outflowing material more or less tangentially of the vortex, and assist the uniform distribution (see Fig. 4).

A valve member 10 of spherical form is mounted upon the end of the compressed gas inlet tube 7 so that by vertical displacement of the latter the flow of pulverulent material from the hopper may be controlled. Control may also be effected by throttling the supply of the compressed gas entering the annulus 3.

In the apparatus shown the solid and gaseous contents of the retort leave together by way of the pipe 11 at the bottom, the extraction of said contents being assisted by a fan or other suitable suction means if desired. The said contents may be delivered either directly or after further treatment to a separator where they are treated in known manner for the separation of the suspended solids, and the gases delivered to plant for the recovery of the more valuable by-products, as is customary. If desired however, separation of the solid and gaseous contents of the retort may take place wholly or partly in the retort itself, for example by forming the lower portion of the retort chamber as a cyclone separator of usual type or by arrangements such as hereinafter described.

If desired the powdered material and gases

may pass through a number of retort chambers in succession, in some or all of which they may be subjected to whirling in a vortex during carbonization as above stated, the temperature being preferably higher in successive retorts. A retort of this character is shown in Fig. 2.

In Fig. 2 a number of retort chambers 12, 13, 14 of a substantially similar form to that shown and described above, are arranged coaxially one above the other, the bottom of one opening directly into the top of the next, and a supply hopper 15 and a feeding and distributing device 16 for the pulverulent material are provided upon the uppermost chamber 12. Through the bottom of the lowermost chamber 14, which tapers downwardly towards a lateral outlet 17, pass a number of concentric tubes 18, 19, 20 which form the eduction pipes for the portions of the contents to be extracted from the central regions of the several chambers. The innermost tube 18 opens at the top adjacent the central region of the uppermost retort chamber 12 and the remaining tubes 19, 20 similarly open respectively into the corresponding lower chambers 13, 14. Below the retort the tubes 18, 19, 20 branch laterally and are adapted for connection to separate pipes for conducting away the products abstracted through the several tubes. Immediately above the upper end of each tube 18, 19, 20 is arranged a deflector or apron 21 of conical form, whilst other deflectors 22 are advantageously mounted immediately below the waist-like junctures between adjacent chambers. These deflectors are conveniently carried by the eduction tubes 19, 18 and in the uppermost chamber 12 upon the bottom of the fuel distributing device 16.

In the operation of the retort above described, for example, for the fractional distillation of powdered coal, according to the preferred arrangement, the particles of coal are fed into the uppermost retort chamber 12 by fuel feeding means such as described above, and mix with the hot gases delivered through the lateral inlets 2' of said chamber. In this chamber the coal is heated to a certain degree, and some of the more volatile constituents may be driven off. Owing to the centrifugal action the heavier fuel particles tend to occupy positions nearer to the walls in the lower part of the chamber, while the lighter gases and vapours tend to occupy the central region of the vortex and may be drawn off through the eduction pipe 18. The heavier portions of the contents of the retort thus do not enter the eduction pipe but descend into the next lower retort chamber 13, at the entrance to which they are deflected somewhat outwardly by the conical deflector 22 and readily mix with the hot gases supplied through the lateral inlets 2' of this chamber. The temperature of the entering gas is preferably somewhat higher than that

of the gas supplied to the previous chamber, and the treatment similarly results in the removal of further volatile constituents through the second eduction pipe 19 and the descent of the heavier particles to the next vortex chamber 14.

This process may be carried out in the successive chambers so that the pulverulent fuel particles leave the final chamber in the form of coke substantially free of volatile matter.

The gases or vapours removed by the several eduction pipes may be delivered to gas treating plant of known kind for the recovery of the by-products, and may incidentally serve to preheat the gas supplied to the several retort chambers. The powdered coke and gases may be removed from the last retort chamber and separated externally thereof in any suitable manner, or the centrifugal action in the last vortex chamber may be utilized to separate the coke finally from the products of distillation.

The action taking place in each retort chamber may be precisely controlled by adjustment of the inlet pressures and temperatures of the gases supplied to the chambers and the pressures in the several eduction pipes. The latter may also be arranged to be adjustable in position so that the products may be removed from the appropriate regions of the retort chambers. Thus, in the construction shown in Fig. 2, the eduction pipes 19, 20 are vertically slideable, and may be appropriately adjusted, for example, by the aid of rack and pinion means 23, 24. Suitable glands 25 are provided to prevent gas leakage.

The arrangement is preferably such that separation of the powdered coke from the gases does not occur in the zone in a chamber immediately opposite to the tangential inlets of the hot gases but at a lower level where the chamber narrows towards the axis, the velocity of the gases and powdered coke being increased somewhat at this narrower region, where the centrifugal separating action is more pronounced. The deflectors aforesaid positioned immediately above the openings of the eduction pipes facilitate the separation and prevent the heavier particles from entering said pipes.

From the above description with reference to Figs. 1 and 2, it will be apparent that the invention may be carried out in various other forms without departing from the spirit or scope thereof. For example, a plurality of eduction pipes may be associated with a single retort chamber, the inlet openings of said pipes being located adjacent different zones in said chamber. Such a construction is illustrated in Fig. 3 which also shows gas inlet means arranged at different regions of the retort chamber.

Thus, referring to Fig. 3, a retort chamber 26 is provided with fuel feeding means 27,

which may be similar to that described above with reference to Fig. 1. Annular gas supply conduits 28, 29 surround the chamber at different levels and communicate therewith by way of inlets 30, 31 disposed more or less tangentially in the walls of the chamber. Eduction conduits 32, 33 extend axially within the chamber 26 and open at different zones therein, said pipes being vertically adjustable substantially as previously described with reference to Fig. 2. Aprons 34, 35 are also provided above the open ends of the eduction conduits. By securing the apron 35, for example, to the end of conduit 33 and providing a sliding engagement thereof with conduit 32, the spacing of said apron above the end of conduit 33 is rendered invariable.

While in the construction shown, the chamber 26 is associated with a further vortex chamber 36 therebeneath provided with gas inlet and eduction means 37, 38 respectively, and a final delivery outlet 39 for the heavier particles remaining after the treatment, it will be apparent that such further retort chamber may in some cases be dispensed with or may be otherwise formed if desired without departing from the invention. Furthermore, while I have shown two sets of gas inlets, each adapted to assist in the creation of vortices in the retort chamber 26, it will be apparent that any desired number of sets of gas inlets may be provided for this purpose, the temperature of the gas entering through said inlets being preferably, but not necessarily, progressively higher in successively lower regions of the retort. For example, in a three-stage process the temperature of the gases entering the successive stages may be 600°-700° F. in the first, 1000° F. in the second and 1300° F. in the third.

It will be understood that the gas employed for ejecting the pulverulent material into the first retort chamber or for treating said material in the several chambers may be gas recovered from the products of the treatment or gas obtained from some other source or air or mixtures of these, according to the character or circumstances of the desired treatment. Also the powdered material may be subjected to preliminary heat treatment before entering the retort.

While the invention is more particularly applicable to the treatment of pulverized fuel it is not necessarily limited in this respect, but may be employed with advantage for roasting other powdered or granular materials, for example, powdered cement, prepared foodstuffs or the like.

While I have shown my invention in a number of preferred forms it will be obvious to those skilled in the art that it is not so limited, but is susceptible of various changes and modifications, without departing from the spirit thereof, and I desire, therefore, that only such limitations shall be placed

thereupon as are imposed by the prior art or as are specifically set forth in the appended claims.

I claim as my invention:—

- 5 1. In apparatus for the heat treatment of pulverulent material, a heating chamber, means for admitting hot gases to the chamber, means for creating a vortex with said gases therein, and means for feeding and distributing said pulverulent material therein, comprising a conduit extending towards the centre of the chamber and terminating in a nozzle device for the ejection of pulverulent material supplied through said conduit.
- 10 15 2. In apparatus for the heat treatment of pulverulent material, a heating chamber, means for admitting hot gases to the chamber, means for creating a vortex with said gases therein, and means for feeding and distributing said pulverulent material therein, comprising a conduit extending within the chamber, a nozzle device mounted thereon and a tube extending within said conduit and nozzle device.
- 20 25 3. In apparatus for the heat treatment of pulverulent material, a heating chamber, means for admitting hot gases to the chamber, means for creating a vortex with said gases therein, and means for feeding and distributing said pulverulent material therein, comprising a conduit extending within the chamber, a nozzle device mounted thereon, a tube extending within said conduit and adjustable longitudinally therein, and valve means for said nozzle device associated with said tube.
- 30 35 4. In apparatus for the heat treatment of pulverulent material, a heating chamber, means for admitting hot gases to the chamber, means for creating a vortex with said gases therein, and means for feeding and distributing said pulverulent material therein, comprising a hopper disposed above the chamber a vertical conduit connected at its upper end to said hopper and at its lower end to a cup-shaped member within said chamber, a longitudinally movable tube within said conduit opening into said cup-shaped member, a valve member carried by said tube in said cup-shaped member, and means for directing material passed through said conduit and cup-shaped member in a direction upwardly and tangentially within the chamber.
- 40 45 50 55 60 65 70 75 80 85 90 95 100 105 110 115 120 125 130 135
5. A retort comprising a plurality of vortex chambers connected in series, means for feeding pulverulent carbonaceous material to the first chamber of said series, substantially tangentially directed gas inlet means arranged peripherally in each of said chambers for supplying gaseous media at relatively high temperatures, gas eduction conduits extending into and opening adjacent the central region of each chamber, and means for adjusting the positions of said conduits in said chambers.
6. A retort comprising a vortex chamber, means for feeding carbonaceous material thereto, substantially tangentially directed inlet means for introducing gaseous media at relatively high temperatures into the chamber so as to create a vortex therein, a gas eduction conduit having an inlet orifice disposed within the central portions of the chamber, and means providing for movement of the inlet orifice so that the gas may be abstracted from any desired point in the chamber.
7. A retort for the fractional distillation of carbonaceous material in pulverulent form comprising a plurality of vortex chambers of roughly pear-shaped configuration, arranged one above the other with the bottom of one opening into the top of the next, tangential gas inlet means disposed at the part of greatest diameter in each chamber for introducing thereinto gaseous media at relatively high temperatures, means for feeding the materials into the uppermost chamber in directions outwardly with respect to the axis thereof, gas eduction pipes extending axially through the retort and opening adjacent the centers of the several chambers, means providing for the withdrawal of the residual products of distillation from the periphery of the lowermost chamber, and means for deflecting the entering material outwardly in each of the chambers below the uppermost chamber.

In testimony whereof I have hereunto subscribed my name this second day of March, 1928.

JAMES NICOLSON BAILEY.
